Des. 186,006

Patented Aug. 25, 1959

186,006

FRONT PANEL FOR FURNACES

George H. Fiedler, Euclid, and John R. Ewart, Cuyahoga Falls, Ohio, assignors to Hupp Corporation, Cleveland, Ohio, a corporation of Virginia

Application November 1, 1957, Serial No. 48,311

Term of patent 14 years

(Cl. D81—19)

Figure 1 is a perspective view of a front panel for a furnace embodying our new design;

Figure 2 is a section taken along line 2—2 of Figure 1;
Figure 3 is a section taken along line 3—3 of Figure 1;
and

Figure 4 is an enlarged fragmentary elevation of the upper portion of the panel.

We claim:

The ornamental design for a front panel for furnaces, substantially as shown.
